AUTOMATIC MANDREL FOR CAPACITOR
WINDING MACHINES

Eugene H. Rich, Pittsfield, and William H. Roberts, Cheshire, Mass., assignors to General Electric Company, a corporation of New York

Application September 13, 1949, Serial No. 115,436

1 Claim. (Cl. 242—55)

1

The present invention relates to machines for automatically winding capacitor rolls and more particularly to an improved automatic mandrel for use in such a machine.

In machines of the type described above, webs of paper and metal foil are moved from reels of the same to a position adjacent a winding mandrel where the webs are assembled in juxtaposition in a predetermined order with the ends of the webs in adjacent relation. The ends of the webs are then clamped between the mandrel sections to be rotated thereby to form a capacitor roll on the mandrel sections and the capacitor roll is thereafter removed from the mandrel sections to permit the winding of a new capacitor roll.

To obtain a maximum production from such a winding machine, it is desirable to reduce to a minimum the inactive time of the machine. By inactive time we mean the time required to remove a wound capacitor roll, clamp the ends of the webs of metal foil and paper between the mandrel sections and begin the winding of a new capacitor roll.

It is an object of this invention to provide an improved capacitor roll automatic winding mandrel and associated mechanism to reduce the inactive time of a capacitor winding machine and thereby increase the production rate of the same.

It is a further object to provide an improved automatic mandrel and associated machinery which may be relied upon to produce a correctly wound capacitor roll.

It is also an object to provide an automatic capacitor roll winding mandrel which may be applied as an attachment to conventional winding machines.

In general, our invention comprises an automatic mandrel having two mandrel sections arranged for cooperative movement to secure webs of metal foil and paper therebetween and wind the same into a capacitor roll, one of the sections being arranged for reciprocal movement along a horizontal longitudinal axis thereof and the other section being arranged for limited movement about a vertical axis.

For a complete understanding of our invention, reference should be had to the following specification and the accompanying drawing in which similar members are given the same character reference. In the drawing, Fig. 1 is a side view partly in cross section of an automatic mandrel illustrative of our invention as applied to a conventional capacitor winding machine portions of which are shown in diagrammatical

2

form, Fig. 2 is a top view partly in cross section of a portion of Fig. 1, and Fig. 3 is an enlarged cross sectional view taken on line 3—3 of Fig. 1 with webs of foil and paper illustrated in Fig. 1 omitted in the interest of simplicity.

Referring to Fig. 1 of the drawing, in accordance with our invention we provide an automatic mandrel 1 horizontally mounted on a table 2 and connected to a vertical frame 3 of a conventional winding machine. The table 2 and the vertical frame 3 are the only portions of the conventional winding machine shown in the drawing as the remaining portions are not necessary to an understanding of our invention. The mandrel 1 comprises two mandrel sections 4 and 5 of circular cross section and having respective adjacent tapered ends 6 and 7, as best shown in Fig. 2. Mandrel sections 4 and 5 are axially aligned one with the other in operating position as shown in Fig. 1 and each of the mandrel sections is journaled to rotate about a common longitudinal axis, as will be described in detail later, to wind a capacitor roll thereon.

In general to secure the adjacent ends of a plurality of webs of metal foil and paper, as indicated at 8, between the tapered ends 6 and 7 of the mandrel sections 4 and 5 and to provide for the automatic removal of a capacitor roll once it is wound on the mandrel sections, we provide means for moving the mandrel section 4 longitudinally toward and away from the mandrel section 5 and means for swinging the end 6 of the mandrel section 5 arcuately in a counterclockwise direction in a horizontal plane as viewed from the top of Fig. 1, and out of alignment with the mandrel section 4 as indicated by the dotted outline in Fig. 2. For a complete understanding of the structure of our invention attention is referred to Figs. 1, 2 and 3 in order. Referring to Fig. 1, one end 9 of the mandrel section 4 is positioned in a cylindrical recess 10 centrally located in one end 11 of a drive shaft member 12 and is secured thereto by a set pin 13 or other suitable means to cause the mandrel section 4 to rotate in unison with the shaft member 12. To permit longitudinal movement of the mandrel section 4, the shaft member 12 is longitudinally positioned in a drive cylinder 14 and secured thereto by keys 15 secured to an end portion 16 of the drive member 12 and arranged for slidable movement in oppositely disposed keyways 17 in the drive cylinder 14. A central portion 18 of the drive shaft member 12 is made of reduced cross section to prevent dirt or other foreign substance from interfering with a longitudinal sliding motion of drive

3

member 12 in the drive cylinder 14. To move the mandrel section 4 longitudinally toward and away from the mandrel section 5 a double acting air cylinder 19 is provided and connected by any suitable means such as a yoke 20, a groove wheel 21 and a connecting rod 22 to end portion 16 of the drive shaft member 12. The groove wheel 21 is rigidly connected to end portion 16 of the drive member 12 to rotate therewith. The yoke 20 slidably engages the groove wheel 21 and remains rotatably stationary.

To rotate the mandrel section 4 through the medium of drive shaft member 12 and drive cylinder 14 any suitable drive means such as a motor 23 is connected to drive cylinder 14 through suitable pulleys 24 and 25 and a belt 26. The pulley 25 is rigidly secured to the drive cylinder 14 to rotate therewith. The drive cylinder 14 is rotatably journaled in vertical plate 3 and a stationary member 27 by suitable bearings 28 positioned in apertures of the plate and stationary member as shown in Fig. 1. One end 30 of mandrel section 5 is positioned in a cylindrical recess 31 centrally located in an end 32 of a second drive shaft member 33 and is secured thereto by a set screw 34 or other suitable means to rotate in unison with drive shaft member 33. Drive shaft member 33 is axially aligned with drive shaft member 12 and is rotatably journaled in a journal member 35 which is supported in a horizontal projecting manner on a bearing post 36 by an angle support member 37 bolted to the journal member and bearing post, as shown in Fig. 1, or by other suitable means.

To rotate the mandrel section 5 in unison with the mandrel section 4, gears 38-45 are interconnected by drive shafts 46-48, as shown in Fig. 1 and the gears 38 and 45 are rigidly connected respectively to the drive cylinder 14 and the second drive shaft member 33. Shaft 48 is longitudinally positioned in a cylindrical aperture 49 centrally located in the bearing post 36, to permit a rotation of bearing post 36 about the longitudinal axis and shaft 48 as will be herein-after described in detail.

To secure the webs of metal foil and paper between the mandrel sections 4 and 5, in addition to the longitudinal reciprocal motion of mandrel section 4, we provide mandrel section 5 with a limited horizontal motion about a vertical axis through the longitudinal axis of shaft 48. This is accomplished by mounting the drive member 33 rotatably in the horizontally positioned projecting journal member 35 and mounting the bearing post 36 in a vertical position on two compression bearings 50. The bearings 50 and the table 2 are apertured as at 52 to accommodate a portion of reduced cross section 53 of the bearing post 36. Bearings 50 surrounding portion 53 of the bearing post 36, ride on opposite faces 54 and 55 of the table 2 and are rotatably secured thereto by a check nut 56 and a shoulder 57 of the bearing post 36 or by other suitable means. The bearing post 36 as so mounted on the plate 2 is free to rotate about the vertical longitudinal axis of shaft 48.

To provide a limited rotation of bearing post 36, journal member 35 and mandrel section 5 about a vertical axis through the center of shaft 48 a double acting air cylinder 58 as shown in Fig. 2 is pivotally connected to one end 59 of an arm 60, the other end 61 of the arm 60 being rigidly connected to a portion of further reduced cross section 62 of the bearing post 36 as shown in Fig. 1.

4

In operation the metal foil and paper are moved from reels of the same to a position above the mandrel sections 4 and 5 and the adjacent ends 8 thereof are moved down to the position shown in Fig. 1. Mandrel section 4 which has been moved to the right is slidably moved to the left by the air cylinder 19 to lie in a position adjacent the ends 8 of the webs and on one side thereof. Mandrel section 5 which has been swung out of longitudinal alignment with the mandrel section 4 that is to the dotted position shown in Fig. 2, by a counterclockwise rotation of bearing post 36 viewed from above the mandrel is now swung back to a position in alignment with the mandrel section 4 and on the other side of the web ends 8 to clamp the webs between the mandrel sections 4 and 5 as shown in Fig. 1.

This is accomplished by energizing air cylinder 58 to rotate the bearing post 36, journal member 35 drive member 33 and the mandrel section 5 in a clockwise direction as viewed in Fig. 2, the bearing post 36 pivoting about the shaft 46 on the compression bearings 50.

To better secure the webs between the mandrel sections 4 and 5, the ends thereof are tapered or otherwise shaped to form mating faces 63 and 64. As the mandrel section 5 is rotated counterclockwise out of alignment with the mandrel section 4 it is also rotated about the common longitudinal axis of mandrel sections 4 and 5 by the gear 45 turning on the then stationary gear 46 thus turning the mating face 63 of mandrel section 5 out of rotary alignment with face 64 of mandrel section 4 which remains stationary. However, when the section 5 is rotated back again into longitudinal alignment with the section 4, gear 44 being stationary the same amount of reverse rotation of gear 45 and mandrel section 5 occurs and therefore the mating faces 63 and 64 are brought back into alignment one with the other.

In addition to maintaining a fixed rotary relation between the mating faces 63 and 64 when the sections 4 and 5 are moved out of alignment thereby to assure their coming together in mating position to secure the webs of metal foil and paper securely therebetween, it is also necessary that the rotation of section 4 be stopped at such a point that the face 64 thereof faces the webs of tape. Otherwise the mating face 63 of section 5 might not be brought into mating position with face 64 of mandrel section 5. For example, if the mandrel section 4 were stopped in such a position that the face 64 thereof was facing away from the foil 8 then the face 63 of mandrel section 5 could not by a clockwise arcuate swing of section 5, be brought into mating position with face 64 of mandrel section 4. Therefore, an end 65 of the drive cylinder 14 is made cam shaped, as shown in Fig. 3, and a stop member 66 operated by a double acting air cylinder 67 or other suitable means is positioned adjacent to the cam end 65 of the drive cylinder 14. In operation when the motor 23 driving the drive cylinder 14 is de-energized, the air cylinder 67 is energized to move the stop member 66 into the path of a projecting portion 68 of the cam 65 thereby to stop the drive cylinder 14 in a predetermined position in which the face 64 of the mandrel section 4 faces the web ends 8.

Once the capacitor roll has been wound on mandrel sections 4 and 5, section 4 is moved to the right by air cylinder 19 thus removing the mandrel section 4 from the wound capacitor

roll. Thereafter, the air cylinder 58 is operated to rotate the mandrel section 5 counterclockwise, as viewed in Fig. 2, in a horizontal plane about a vertical axis through the shaft 48. This operation places the mandrel section 5 and associated mechanism in the position indicated by the dotted portion of Fig. 2. To remove a wound capacitor roll from the mandrel section 5 a stripping member 69 comprising a cylindrical mandrel rider 70 having a frustoconically shaped end 71 is positioned to surround the mandrel 5 and is connected by linkage 72 to a double acting air cylinder 73. In operation as mandrel section 5 is being arcuately moved out of longitudinal alignment with the mandrel section 4 the air cylinder 73 is operated to move the rider 70 forward on the mandrel section 5 to engage and eject the wound capacitor roll. Thereafter mandrel section 4 is moved forward to a position adjacent a new web end 8 and mandrel section 5 is rotated clockwise back into longitudinal alignment with mandrel section 4 to secure the new web ends 8 between the mandrel sections 4 and 5 and at the same time the rider 70 is retracted by the air cylinder 73, to its original position as shown in Fig. 1. The automatic mandrel is now ready to begin the winding of a new capacitor roll.

One advantage of our invention lies in the fact that by use of our automatic winding mandrel the inactive time otherwise required to eject a wound capacitor roll and begin the winding of a new one is considerably reduced.

Another advantage of our automatic mandrel is that it is adaptable to and may be used on conventional winding machines.

A further advantage of our automatic winding mandrel is that it provides a means positively driving each of the mandrel sections in unison at a predetermined speed of rotation.

A still further advantage of our invention is provided in that accurate, reliable alignment of the mating faces of the mandrel sections is accomplished after a rapid ejection of a wound capacitor roll.

While we have shown and described a particular embodiment of our invention, it will be obvious to those skilled in the art that various changes and modifications may be made without departing from our invention in its broader aspects and we, therefore, aim in the appended claim to cover all such changes and modifications as fall within the true spirit and scope of our invention.

What we claim as new and desire to secure by Letters Patent of the United States is:

In a high speed capacitor roll winding machine having a plurality of reels for holding webs of metal foil and paper and having means

for assembling these webs in juxtaposition in a predetermined and vertically disposed order with the ends of the webs in adjacent relation, a mandrel made of two elongated rotatable sections, said sections being rigidly and respectively mounted horizontally on rotatable shafts and alignable one with the other so as to be rotatable about a common longitudinal axis, a drive cylinder rotatable about said longitudinal axis, one of said rotatable shafts being slidably positioned in and keyed to said drive cylinder to effect rotation of said one shaft and said mandrel section mounted thereon, a double acting air cylinder connected to said one shaft to provide slidable reciprocal motion thereof and said mandrel section mounted thereon within said drive cylinder and along said common longitudinal axis, a bearing post mounted for limited rotation about a vertical axis, a journal member mounted on said bearing post and rotatable therewith about said vertical axis, said other rotatable shaft being horizontally and rotatably mounted in said journal member, a second double acting air cylinder connected to said bearing post to effect rotation thereof and limited arcuate horizontal motion of said other rotatable shaft and said other mandrel section mounted thereon about said vertical axis and with respect to said common longitudinal axis, tapered surfaces respectively on said mandrel sections adapted for cooperative mating with each other when said other rotatable shaft is aligned with said common longitudinal axis, means comprising a cam fixed to said drive cylinder and a stop engageable with said cam to stop rotation of said shafts and mandrel sections in a position so that said mating surfaces thereon will face each other and said vertically disposed webs may be received and secured therebetween, and ejector means mounted on said journal member slidably adjacent and with respect to said other rotatable shaft for automatically ejecting a capacitor roll from said mandrel section mounted thereon after the roll is wound.
